UNITED STATES PATENT OFFICE.

FREDERICK SIEGEL, OF IRVINGTON, NEW JERSEY, ASSIGNOR TO AUTO RADIATOR COMPANY, A CORPORATION OF NEW JERSEY.

METHOD FOR PRODUCING RADIATORS FOR AUTOMOBILES.

1,242,952

Specification of Letters Patent.

Patented Oct. 9, 1917.

Application filed March 2, 1917. Serial No. 152,036.

To all whom it may concern:

Be it known that I, FREDERICK SIEGEL, citizen of the United States, residing at Irvington, Essex county, State of New Jersey, have invented certain new and useful Improvements in Methods for Producing Radiators for Automobiles, of which the following is a specification.

My invention relates to processes for making water cooling devices, and more particularly to methods of producing radiators for automobiles and other uses.

An object of my improved process is to produce a device of the class described which is more durable, more easily repaired and restored when injured or damaged, and which can be manufactured with less labor and at correspondingly reduced cost.

My process generically described comprises two principal steps or stages of which the first comprises the preparation of a core or matrix of peculiar design and construction, upon which an electro-deposit may be formed: and then in subjecting the core thus prepared to the electrolytic process immediately, that is, without other preliminary or intervening steps, producing thereby a perfectly formed radiator which not only possesses, among other characteristics, a smooth interior surface due to the manner in which the core-matrix has been freed from impurities and imperfections in casting, but which also, owing to form of arrangement of all its surfaces, receives the deposit uniformly throughout the entire area of the shell formed thereby.

My method more particularly described, therefore, consists in the method employed for producing the core or matrix of improved quality as to the nature of the composition thereof, and in the peculiar features which characterize the conformation or design thereof, having reference to the particular bevel employed at the edges and in the apertures piercing the body portion. That is to say, the finished product of my present process is a one-piece radiator having two similar parallel faces seamlessly joined at their sides by oblique surfaces, and which are further connected by numerous tubular openings with similarly inclined surfaces for the passage of air currents therethrough; so that all surfaces, including the parallel faces, the connecting edges and the intermediate apertures, constitute a continu-

ous integral surface of substantially uniform thickness throughout, and so disposed that a maximum surface area of the radiator may be subjected to the action of the cooling element.

Heretofore, many attempts to produce an article of the description indicated have not only been laborious and expensive in methods employed that have comprised complications which I have eliminated but such attempts have also been rendered unsuccessful by reason of the faulty manner in which the core member has been made, in that it usually contained impurities and defects in its composition, that have detracted from the indispensable degree of smoothness required in the matrix of this type.

The first above mentioned deficiency has been overcome in the present method by the simple expediency of adapting the form of the connecting surfaces, namely, the tubes, so called, and the edges, so that they will receive the deposit directly upon the faces of the matrix at a single emersion thereof in the electrolytic bath, in which direct process the complete radiator shell is produced in the final form required. To this end at both the front and rear surfaces of the shell, I incline or bevel the edges of the respective sides, and likewise the surfaces within the ducts or apertures at approximately forty-five degrees or less, relatively to the respective planes of the two parallel faces constituting said front and back portions. That is, a like area of the declivity or the bevels specified is presented at both the front and rear sides of the matrix member, so that when that member is employed as the cathode and is exposed to the direct impact of the ions of the electrolytic deposit which play simultaneously from the oppositely disposed anodes, it receives an almost equal depth of deposit upon the inclined as upon the other surfaces thereof.

In addition to the advantages of the special form of matrix core employed in the practice of my process, I further improve the resulting deposit over the surfaces thereof by reason of the high degree of homogeneity of the material comprising the matrix.

Thus, the difficulties and deficiencies heretofore existing in matrix cores due to the presence of foreign matter in the casting I eliminate in the direct and simple manner.

of introducing the molten material into and through the bottom of the mold, employing a U-shaped section for the purpose immediately adjacent the point of connection 5 with the mold. This U-shaped construction of the tube for conducting the molten metal into the mold, constitutes a type of trap for liquids and has an arm reaching above the height of the pattern in which the metal is 10 to be cast, at the top of which is retained the dross and the innumerable air sacks and blow-holes incident to the pouring, while the pure metal flowing through the trap at the bottom of the U-tube enters the casting entirely free from such impurities.

The mold which I preferably employ is of the so-called split type, that is, it is made up of two similar members, having their inner and oppositely disposed faces recessed in 20 conformity to the general outlines of the radiator, and in depth are equal substantially to one-half the thickness of the core or matrix to be cast therein; so that when the members are brought together they constitute a hollow chamber corresponding to the design of the shell required. The orifice through which the metal is poured in casting the matrix, is placed at the bottom of the mold, the metal being conducted 25 thereinto through the U-shaped section or trap described above, the open arm of which, as pointed out, extends above the level of the mold. At the upper edge of the mold are provided vent holes necessary for the escape 30 of air that is displaced by the metal.

In the practice of my invention I preferably employ apparatus substantially as above set forth to supply convenient means for attainment of the result of the within 40 described process, which however do not constitute indispensable elements of my improved method of producing radiator shells and similar articles.

The appliances thus preferably employed 45 in obtaining the results indicated are illustrated in the preferred forms thereof in the accompanying drawing, of which—

Figure 1 is an elevation of the core or matrix; 50 Fig. 2 is an enlarged partial sectional view thereof;

Fig. 3 is a similar sectional view of the core shown in Fig. 2 with a deposit thereon in the form in which it comes from the 55 electrolytic bath;

Fig. 4 is a like sectional view of the shell after the core has been removed;

Fig. 5 is an upright sectional view of the mold having attached to the bottom thereof 60 a bent tube through which molten metal may be introduced into the mold.

Referring to the drawings: 10 represents a core-matrix (Figs. 1 and 2), which is made of a metal having a lower melting point than that of the electro-deposit to be

laid thereon, preferably of lead or some suitable alloy thereof.

The matrix is perforated practically throughout its entire area by a plurality of orifices 12 having at the opposite sides similarly beveled faces or flaring mouths 13. These perforations are preferably arranged in horizontal rows so that an orifice of one row is immediately under the solid material separating those of the adjacent rows, 75 such offset arrangements being designed to produce a radiator having its air conducting tubes in a position to divide the contained fluid of the radiator and thereby extend the circulation to the full width of the 80 radiator, in thus passing from the top toward the bottom thereof. The exact arrangement of placing one orifice equally distant from those next above or below is not, however, a controlling feature of my invention, it being preferable in any event, however, to have those ducts "staggered" 85 in some similar manner.

The respective sides 11 of the matrix are given a similar bevel to that of the orifices, 90 which for the connecting surfaces along the sides as well as those within the orifices, in the preferred form of my process, is fixed at an angle of approximately 45° to the respective parallel faces of the matrix. This 95 specified inclination or bevel of the so-called connecting surfaces has been fixed upon for important reasons, among which are the following: first, that in the usual electrolytic process a deposit can be made upon a surface of such a prescribed declivity at about the same rate of deposit as upon the surface at right angles to the line of impact of the particles deposited thereon; and, secondly, for the reason that this arrangement 100 produces the maximum efficiency for reducing the temperature of its circulating contents and is possessed of great strength, combined with a certain degree of elastic yield. As the anodes are placed several inches from the surface or sides of the matrix, the fraction of an inch in the difference between the apex of the angles on the surface or sides of the matrix and the apex of the angles between the orifices will cause no appreciable difference in the thickness of the deposition of copper.

It is apparent that a more acute angle than 45° will reduce proportionately the radiating surface and that a more obtuse angle 110 will cause an unequal deposition of copper. I have therefore found that apertures with a bevel of substantially the 45° obliquity specified enhance the temperature reducing efficiency of radiator shells of this general 115 construction. It is also apparent that if this bevel be reduced less resistance would be offered to the air or other medium passing through the perforation, for which reason the air is less dense and possessed of a lower 120 125 130

capacity for heat absorption, such reduction in cooling efficiency continuing proportionately as the sides of the tube approach the lines of a straight bore; on the other hand should this bevel be flattened, while for reasons indicated the cooling action of a given co-efficient of air would be improved, yet the distance between the parallel faces would accordingly diminish, correspondingly reducing the circulation capacity of the radiator unless the form of the apertures be modified, which would give rise to complications and considerations not deemed necessary to explain in the present connection.

15 Furthermore, the bevels of the opposite sides at the point of their intersection form a ninety degrees angle within the shell which in itself possesses a twofold advantage of stiffening and bracing the shell most effectively, and also of providing against forming narrow internal crevices, for the accumulation of solids, deposits and other deleterious accretions which would accumulate at those seams, if a more acute convergence of the two bevel surfaces were permitted.

These beveled surfaces of the apertures 12, as has been seen, are similar in form and area at the respective front and rear sides of 30 the radiator, so that a deposit is simultaneously applied upon the opposite faces and when the process is complete a continuous, unbroken union is made between the parallel faces connected thereby with the advantageous results as pointed out.

35 The mold 20 is made up of two similar side members 21, each having a recess 23 conforming to the outlines of the core to be cast therein and is held together by bolts 26 having an opening provided with a nipple 25 at the bottom and vent holes 24 at the top.

To the nipple 25 is attached the short arm of a U-shaped tube 39, having a long arm

32 with a flaring funnel mouth 33 for receiving the molten metal therein, and a trap section 31 at the bottommost portion thereof, through which the metal passes before entering the mold.

40 The matrix core thus produced is introduced into an electrolytic bath in the usual manner of electroplating, and a deposit preferably of copper is allowed to cover all the surfaces of the matrix to the required thickness, and thereupon sufficient heat is applied to the matrix to melt the core which flows out through the opening at the bottom made in the shell of the radiator to be ultimately used for connecting the water circulation.

45 Having described my invention, what I claim is:

1. A method of making radiator bodies comprising the formation from a metal of a low fusing point of a matrix core having 50 parallel faces and beveled connecting surfaces of approximately 45° declivity, depositing a metal shell of substantially uniform form thickness on said faces and said beveled surfaces; and removing the core from the 55 shell.

2. A method of making radiator bodies comprising the formation from a metal of a low fusing point of a matrix core having 60 parallel faces and beveled connecting surfaces of approximately 45° declivity, depositing a metal shell of substantially uniform 65 thickness on said faces and said beveled surfaces; and removing the core from the 70 shell by melting the core.

75 In testimony whereof, I have signed my name to this specification in the presence of two subscribing witnesses, this 24th day of February, 1917.

FREDERICK SIEGEL.
